UNITED STATES PATENT OFFICE.

JAMES COOKE, OF NEW YORK, N. Y., ASSIGNOR OF ONE-HALF TO WILCOX A. CREAMER, OF BROOKLYN, NEW YORK.

INCANDESCENT-LAMP LOCK.

Application filed March 12, 1927. Serial No. 174,875.

The main object of the present invention is to provide improved means for preventing the unauthorized removal and theft of an electric lamp bulb from its socket.

5 Other objects will appear hereinafter.

In the drawings:

Fig. 1 is a side view partly in section showing a lamp bulb and socket held together by my improved retaining means;

10 Fig. 2 a side elevation of the joint between the lamp and socket;

Fig. 3 a detail side view of the plug end of the lamp, partly broken away;

15 Fig. 4 a detail plan view of the annular lamp-retaining band showing it expanded; and

Fig. 5 a detail plan view of said band partly in section showing it contracted and with its ends secured together.

20 Referring by numerals to the various parts, 1 designates the lamp socket and 2 the glass incandescent lamp bulb carried thereby. The socket 1 is formed with an annular bead 3 adjacent its open end. This bead is present in practically all of the commercial 25 sockets now in use.

The lamp 2 is provided at one end with the usual threaded metal plug 4 which is adapted to screw into the socket. Closely 30 adjacent to the plug 4 the bulb is integrally formed with an annular glass bead or rib 5 which extends entirely around the bulb and is formed to provide an annular locking shoulder 6. The shoulder 6 faces away from the plug 4, toward the opposite end of the lamp, and its purpose will be presently set forth. The diameter of the bead 5 is substantially equal to that of the bead 3 upon the socket.

40 A locking member 7 is provided for locking the lamp and socket together. This member is in the form of a somewhat flexible and resilient sheet metal band formed into a split annular shape, as shown in Figs. 4 and 5. The ends of the band are bent radially outward to provide two opposed fastening ears 8 which are formed with apertures. One edge of the band 7 is turned inwardly to form an annular retaining flange 9 extending around the band from one of the ears 8 to the other. The opposite edge of the band is formed with a similar retaining flange 10.

Prior to screwing the lamp into the 55 socket the band 7 is placed around either

the open end of the socket or the plug end of the lamp. The width of the band is such that the space between its flanges 9 and 10 will accommodate both the bead 3 and the bead 5 when the lamp is screwed into the 60 socket, as shown in Fig. 1. When the band has been adjusted around said beads the flange 10 engages the locking shoulder 6 and the flange 9 engages the bead 3 at the side thereof remote from the bead 5. The ears 65 8 of the locking band are then brought together to contract the band and are rigidly secured in closed position by a tubular rivet 11 inserted through their apertures. This rivet is preferably of comparatively soft 70 metal so that it may be readily placed in position and secured to the ears 8 by a hand tool. While I prefer to use a rivet it will be understood that other suitable fastening means may be employed to hold the locking 75 band closed. The bulb and locking band have been particularly designed for attachment to sockets of standard form and thereby avoid the necessity of altering or replacing standard fixtures in order to lock the 80 bulb.

When the parts are assembled as shown in Figs. 1 and 2 it will be impossible to detach the lamp from the socket except by the removal of the locking band. The lamp, 85 however, may be turned slightly in the lamp socket. This is desirable for the reason that if the lamp were rigidly locked against all movement it would likely be broken by persons endeavoring to detach it. If, however, 90 the lamp turns for a limited distance and then becomes rigidly locked between the flanges 9 and 10 they are warned that the lamp is not held in position in the ordinary manner and consequently they will be discouraged from further efforts to remove it. The lamp is held against withdrawal by the engagement of its rib 5 with the flange 10 of the locking ring. This rib is nonconducting, being formed of glass integrally with the 100 lamp, and the necessity for providing insulating means between the band 7 and the plug 4 is thereby avoided. This manner of connecting the locking ring to the lamp positively guards against any possibility of a short circuit through the plug 4, the locking ring and the metal shell of the socket, and thus complies with the safety requirements of the fire underwriters. While the locking band holds the lamp against with- 105 110

drawal it is so designed as to leave the lamp free to be screwed into the socket as far as may be necessary to make a good contact. When it is necessary to remove the lamp the rivet 11 may be removed by a suitable hand tool. The locking band can then be expanded to free the beads 3 and 5 and permit the lamp to unscrew.

It will be obvious from the foregoing that I have provided an extremely simple, safe, effective and inexpensive means for preventing the unauthorized removal and theft of electric bulbs. In hotels, office buildings, factories, etc., considerable loss results from the theft of incandescent lamp bulbs. In some cases this loss is so great as to call for the employment of men to act as guards to prevent theft. In hotels it frequently occurs that the guests remove the lamp bulbs from the sockets and connect chafing dishes and other electric cooking utensils and electrically heated irons to the light circuit. This frequently results in over-loading the circuit and the consequent burning out of the fuses. Where the fuses are not destroyed there is an excessive consumption of current which is a direct loss to the hotel.

While I have described and shown what I now consider the preferred form of my invention I reserve the right to make such changes therein as will lie within the scope of the claims.

What I claim is:

1. The combination of a lamp socket; an electric lamp in the form of a glass bulb provided with a screw plug adapted to fit said socket; a non-conducting locking shoulder directly and rigidly carried by the lamp bulb adjacent the screw plug and retaining means to connect said locking shoulder with the socket and prevent the removal of the bulb from the socket.

2. The combination of a lamp socket having an annular bead near its open end; a glass lamp bulb provided with a screw plug adapted to fit said socket and formed integrally with a locking shoulder adjacent said plug and facing away from it toward the opposite end of the lamp and retaining means to connect said bead and locking shoulder and prevent removal of the lamp from the socket.

3. The combination of a lamp socket hav-

ing an annular bead near its open end; a glass lamp bulb provided with a screw plug adapted to fit said socket; a glass rib integrally formed upon the bulb, extending around it adjacent the plug, and providing a locking shoulder directed away from the plug; a split annular flexible locking member adapted to surround the open end of the socket and the plug end of the lamp, formed with an inturned retaining flange at one edge to engage said locking shoulder, and formed with an inturned retaining flange at its opposite edge to engage the side of the socket bead directed away from the locking shoulder, the ends of the locking member being formed with outturned ears adapted to be secured together, whereby said member will hold the lamp to the socket.

4. An electric lamp comprising a glass bulb provided with a screw plug at one end and integrally formed at its outer surface with a locking shoulder adjacent the plug and facing toward the opposite end of the lamp.

5. An electric lamp comprising a glass bulb, formed with a plug end; a metal screw plug mounted upon said end of the lamp; and an annular glass bead integrally formed upon the bulb, extending around the outer surface thereof adjacent said metal plug and formed to provide a locking shoulder facing toward the opposite end of the bulb away from the plug.

6. An electric lamp comprising a bulb provided with a screw plug at one end and a non-conducting locking abutment permanently carried by the lamp adjacent the inner end of the plug and facing toward the bulb end of the lamp for the purpose set forth.

7. The combination of an electric lamp comprising a glass bulb provided with a screw plug at one end; a non-conducting locking abutment permanently carried by the lamp adjacent the inner end of the plug and facing toward the bulb end of the lamp; and a split, annular locking member formed to engage said locking shoulder and to engage a lamp socket member to hold the lamp against removal from the socket member.

In testimony whereof I hereunto affix my signature.

JAMES COOKE.
